B. WILLIS.

STATEMENT SHEET.

APPLICATION FILED JULY 5, 1916.

1,244,815.

Patented Oct. 30, 1917.

INVENTOR:

BARNAGO WILLIS,

By *Knight Cook*

UNITED STATES PATENT OFFICE.

BARNARD WILLIS, OF ST. LOUIS, MISSOURI, ASSIGNOR TO GEO. D. BARNARD & COMPANY, OF ST. LOUIS, MISSOURI, A CORPORATION OF MISSOURI.

STATEMENT-SHEET.

1,244,815.

Specification of Letters Patent. Patented Oct. 30, 1917.

Application filed July 5, 1916. Serial No. 107,539.

To all whom it may concern:

Be it known that I, BARNARD WILLIS, a citizen of the United States of America, a resident of the city of St. Louis, State of Missouri, have invented certain new and useful Improvements in Statement-Sheets, of which the following is a full, clear, and exact description, reference being had to the accompanying drawing, forming a part of this specification.

My invention relates to a foldable statement sheet, and has for its object the production of a simple and inexpensive statement sheet having its elements so shaped and arranged that the address on the statement will serve as the mailing address, without using a separate envelop as a container for the statement and adapted to be used as an inclosing envelop for loose matter accompanying the statement.

Figure I is a perspective view of a statement sheet embodying the features of the invention.

Fig. II is a perspective view illustrating the sheet as it appears after the first folding operation, a portion of the sheet being broken away to show the cancelled bank checks which are to be inclosed in the folded article.

Fig. III illustrates the sheet as it appears immediately before the final folding operations.

Fig. IV shows the addressed envelop produced by folding and sealing the statement sheet.

Fig. V is a fragmentary front elevation.

The blank shown in Fig. I is preferably, not essentially, scored along the lines 1, 2, 3, 4 and 5 to form an address section A at the top of the sheet, a window section B at the bottom of the sheet, intermediate statement sections C and D between the address section and window section, and ungummed flaps E which extend from the intermediate section C. A window 6 is formed in the window section B, and the lower margin 7 of this section is gummed to provide a simple means for securing the sheet in its folded condition.

The article I have shown is a statement sheet adapted to be used by a bank in rendering a statement to a depositor, at the same time serving as a container for the canceled checks.

After the statement has been written in the usual manner, the name and address of the

depositor will appear near the top of the sheet, on the address section A, as shown in Fig. I.

The matter to be inclosed by the statement sheet is placed upon the intermediate section C, and after the sheet has been folded on the fold score 2, the different sections will occupy the relative positions shown in Fig. II. The address section A is then folded backwardly, onto the back of the intermediate section D as shown in Fig. III. It is important to note at this time that the address section A is narrower than the other sections, and when this narrow section is folded backwardly (Fig. III) it does not completely cover the intermediate section D. In Fig. III, it is seen that the face of the narrow address section A is partly exposed so that the address thereon will serve as the mailing address, and that the portion of the section D not covered by reason of the narrowness of section A is exposed to receive the gummed margin of the window section. Before sealing the article, the ungummed flaps E are folded over the intermediate sections C and D, and also over the narrow address section A. The window section B is then folded over all of the other elements and its gummed margin 7 is stuck onto the ungummed flaps E and onto the back of the intermediate section D. The folded statement sheet will then constitute a sealed envelop (Fig. IV) in which the address will be seen through the window 6 of the window section B.

Since the address section A (Fig. III) is narrower than the other sections, the gummed lower margin of window section B will overlie the section D at a point beyond said address section. The window section B will, therefore, be cemented to the back of the statement sheet, instead of to the front of the address section.

To open the envelop, a knife may be inserted under one of the non-adhering flaps E at the point indicated by X in Fig. IV, and by cutting along three margins of the envelop as indicated by arrows, the flaps E and the window section will be severed from the intermediate section C. The window section A and flaps E will remain fastened to the back of the statement sheet by the adhesive material on the window section, but the article may be readily unfolded to expose the entire statement which appears on the sections

A, D and C, none of the severed elements being attached to the face of the statement sheet.

I claim:—

5 A combined statement sheet and inclosing envelop having at its upper end a narrow address section, at its lower end a section provided with a lower gummed margin, an ungummed portion wider than the narrow address section and a window for exposing an address, on the narrow address section when the sheet is folded, and, intermediately, 10 statement sections and a plurality of ungummed flaps carried by the ends of one of the statement sections and adapted to com-

plete a sealed inclosure for loose matter when one of the statement sections is folded over the other statement section, the address section folded backwardly over the last mentioned statement section, the ungummed flaps folded inwardly over the statement sections and over the address section, the window section folded over the address section and the ungummed flaps and the gummed margin of the window section gummed to the flaps and to the back of the adjacent statement section on the same side as and at a point beyond the address section. 20 25

BARNARD WILLIS.
